Des. 204,831
Patented May 17, 1966

204,831

ACTUATOR FOR A PRESSURIZED CAN

Irving B. Goldberg, 425 W. Aldine Ave.,
Chicago, Ill. 6057

Filed Jan. 26, 1965, Ser. No. 83,589

Term of patent 14 years

(Cl. D58—26)

Fig. 1

Fig. 2

Fig. 3

FIGURE 1 is a front perspective view of an actuator for a pressurized can embodying the new design;

FIGURE 2 is a top plan view of the actuator for a pressurized can of FIGURE 1;

FIGURE 3 is a side elevational view looking from the bottom of FIGURE 2, the opposite side being the same in appearance;

FIGURE 4 is an end elevational view looking from the left of FIGURE 3;

FIGURE 5 is an end elevational view looking from the right of FIGURE 3; and

FIGURE 6 is a bottom plan view.

I claim:

The ornamental design for an actuator for a pressurized can, substantially as shown and described.
